MOUNTING FOR PRINTING MACHINE
COLOR PANS

Horace L. Babson, Rock Hill, S. C.

Application December 15, 1939, Serial No. 309,309

5 Claims. (Cl. 101—364)

This invention relates to printing machines, and more particularly to color pans and their mountings used in connection with textile printing machines.

Heretofore, the practice has been generally to secure the pan to the machine by means of large detachable clamps. In order to change the pattern being printed by the machine, it is necessary to remove the color pan and necessarily the holding clamps. These changes are apt to be frequent and the wear on the clamps is considerable. A wrench is required to tighten or loosen the set screws and the threads are soon stripped. The pressure of the clamps also warps the pans and chews up the supporting members.

During the pattern changes there is the possibility of the clamps or the wrenches being misplaced, with the resultant loss of time. Occasionally the clamps work loose while the machine is in operation and the pan slips off the supports, resulting not only in the loss of expensive dye but of unprinted cloth passing through the machine before it can be stopped. These are some of the difficulties encountered in the normal operation of this type of printing machines and which are overcome by the present invention.

It is an object of the present invention, therefore, to provide novel means for mounting a color pan in connection with a printing machine which will greatly increase the speed and facility with which the pan can be removed from and installed in operating position.

It is another object to provide supporting means which are simple in construction and inexpensive to manufacture.

It is a further object to provide supporting means which minimize the wear and strain on the various parts.

It is another object to provide supporting means for a color pan which will prevent the pan from becoming dislodged unintentionally.

It is a further object to provide efficient supporting means for a color pan which are readily adaptable to the ordinary printing machine without necessitating any change in the construction of the color pan or the machine itself and which may be easily installed on the machine.

It is another object of this invention to provide means for supporting a color pan which will increase the operating efficiency of a printing machine and also improve its appearance.

These and other objects not specifically enumerated are contemplated for this invention, as will readily appear to one skilled in the art as the following description proceeds.

The accompanying drawing is a fragmentary perspective view of a color pan holder constructed in accordance with the present invention and installed on a printing machine.

Referring to the drawing more in detail, the machine frame is of suitable construction for the accommodation of the operating mechanisms, and consists, essentially, of the end frames 5, one of which is omitted from the drawing for the sake of clearness. A large cylinder or boss roller 6 is provided with journals 7 which are supported by the end frames 5. A printing roller 8 is journaled in the split bearings 25. The block 26 is slidably mounted in an opening in the end frame and is moved toward the journal 27 by the jack screw 28 which is threaded through a portion of the end frame and engages the block. The printing roller may be removed by unscrewing the jack screw. The block 26 moving away from journal 27 opens the split bearing 25, thereby permitting the roller to be lifted out. It is, of course, necessary to remove the color pan 11 and furnisher 10, as described below, before the printing roller may be removed. The surface of the printing roller has the design engraved on it which is to be transferred to the cloth 9 as it passes between rollers 6 and 8.

Furnisher roller 10 is supported by the color pan 11 which provides bearings 12 for the journals 13 of the furnisher. The color pan is provided with flanges 14 adjacent the ends which are supported by the steps 15. The steps are provided with a U-shaped slot, and the upper member 16 and lower member 17 have a series of aligned openings 18. The flanges 14 are each provided with an opening which, when positioned between corresponding openings 18 in members 16 and 17, are in alignment with them. When so aligned, a pin 19 may be passed through the openings. The pin 19 has a shoulder 20 which prevents it from passing all the way through the openings. This pin may be secured to the step with a chain 21 which will prevent it from being misplaced when not in use.

Step 15 is L-shaped and is supported adjacent its upper end 22, which is threaded and freely passes through a lug 23 on the block 26. A wing nut 24 is screwed onto the threaded end above the lug. The step, together with the color pan and furnisher, may be raised or lowered by screwing or unscrewing the nut 24.

In order to change the printing roller 8 or the color in the color pan 11, the pins 19, which pass through openings in the upper members 16, the flanges 14 of the color pan, and the lower mem-

bers 17 of the steps, are lifted out, leaving the flanges 14 free to be slipped out of the open-ended slots in the steps 15. The furnisher roller may then be lifted out of the pan and the color changed. Similarly, in replacing the furnisher and pan, it is merely necessary to slide the flanges 14 into the slots formed by the upper and lower members 16 and 17 until the furnisher is in the desired position, and then dropping pins 19 through the aligned openings. The position of the color pan may be varied by sliding it forward or back and dropping the pin in a different set of openings in the members 16 and 17. The color pan and furnisher roller are held firmly in place and cannot work loose. It is necessary for the operator to remove the pins before the pan and furnisher may be removed; consequently the possibility of the pan becoming accidentally dislodged while the machine is in operation is eliminated.

It is to be understood that the particular shape of the step 15 and the means for securing it to the machine and adjusting its position with respect thereto, as disclosed in the drawing and specification, are only by way of illustration and that the present invention may be used in connection with various types of printing machines having different types of steps and mountings therefor.

30. What is claimed is:

1. In combination with a printing machine, a color pan having flanges adjacent the ends thereof provided with openings, steps for supporting said pan in operative position with respect to said machine, comprising a pair of U-shaped members forming open-ended slots for receiving said flanges and being provided with aligned openings, and removable means passing through said first and second-named openings for maintaining the position of said flanges with respect to said members.

2. In combination with a printing machine, a

color pan having flanges adjacent the ends thereof provided with openings, means for supporting said pan in operative position with respect to said machine, comprising a pair of oppositely disposed steps having upper and lower members forming slots to receive said flanges and having a plurality of aligned openings therein, and removable means for selectively maintaining the alignment of the openings in said flanges with those in said members.

3. In combination with a printing machine, a color pan provided with extended end portions having an opening in each, means for removably supporting said color pan in operative position with respect to said machine, including upper and lower members forming slots to receive said end portions and having a series of aligned openings therein, and removable means for selectively maintaining the openings in said end portions in alignment with the aligned openings of said upper and lower members.

4. In combination with a printing machine, a color pan having extended end portions with openings therein, means for removably supporting said color pan in operative position with respect to said machine, including steps underlying said end portions for supporting them, and being provided with openings therein, and removable means for maintaining the openings in said end portions in alignment with those in the steps.

5. In combination with a printing machine, a color pan member, a member for supporting said pan member in operative position with respect to said machine, portions forming slots and having openings therein provided by one of said members, means for entering said slots and having openings therein provided by the other of said members, and means for maintaining the alignment of the openings in said slot-forming portions and said slot entering means.

HORACE L. BABSON.
